his ATTORNEY.

UNITED STATES PATENT OFFICE

THEODORE A. FEDERWITZ, OF PHILADELPHIA, PENNSYLVANIA, ASSIGNOR TO STOKES & SMITH COMPANY, OF PHILADELPHIA, PENNSYLVANIA, A CORPORATION OF PENNSYLVANIA

METHOD OF AND APPARATUS FOR WRAPPING BOXES

Application filed February 12, 1929. Serial No. 339,426.

My invention relates to the art of applying individual sheets, wrappers, labels, or the like, hereinafter generically termed "wrappers" to cartons, containers, boxes and the like, hereinafter termed "boxes."

In accordance with my invention, to permit high speed of wrapping of a box, without the usual attendant mutilation or tearing of the wrapper being applied thereto, a blast 10 of air is directed against one or more wrapper portions or panels to hold them out of the path of movement of another or other wrapper portions, specifically corner-lap sections, being folded into engagement with the box.

15 My invention resides in the method, systems, features of construction and arrangement hereinafter described and claimed.

For an understanding of my invention and for illustration of one of the forms it may 20 take, reference is made to the accompanying drawing, in which:

Fig. 1 discloses a side elevational view of a box wrapping machine, utilizing my invention.

25 Fig. 2 is a fragmentary view of parts shown in Fig. 1.

Fig. 3 is an end elevational view of parts shown in Fig. 2.

Fig. 4 is a top plan view of parts shown 30 in Figs. 1, 2 and 3.

Figs. 5 and 6 represent successive steps in the application of a wrapper to a box in accordance with a prior practice.

35 Figs. 7, 8 and 9 illustrate the position of wrapper panels during the application of a wrapper to a box in accordance with my invention.

Referring particularly to Fig. 1, within 40 the hollow casing 1 mounted upon a base 2 is disposed a drum cam, not shown, effecting oscillations of a lever 3 about its pivot pin 4 suitably supported for rotation in member 5 integral with or attached to casing 1. To the outer end of the lever 3 is pivotally 45 mounted a link member 6, threadably and adjustably engaging a yoke member 7 through the upstanding arms of which and an actuating arm 8 passes a connecting pin 9. One end of arm 8 is connected by suitable link- 50 age, as lever 13 to a plunger rod 14 guided

for vertical reciprocating movement by guide member 15 suitably secured to the standard 11 as by bolts 16. To the lower end of the plunger rod 14 are attached the form blocks 17 and 18 adapted to receive and snugly fit 55 into a box B to be wrapped, or to support the walls of an unstayed box to be wrapped and stayed.

A tension spring 10, the lower end of which is suitably connected to a retaining member 10^a pivoted to goose-neck or standard 11, and the upper end of which is connected to a retaining collar threaded on adjusting screw 10^b which slidably engages a pin at the end 60 of actuating arm 8, balances the reciprocating form-block structure and its actuating mechanism including plunger 14, arm 8, etc.

As the plunger moves downwardly from the position shown in Fig. 1, there is engaged a lower form-block or platen 19 carried by a plunger 20, biased by a spring to the position shown in Fig. 1, and thereafter the platen 19 is moved downwardly during continued movement of and with plunger 14. 70

At the conclusion of the wrapping operation which is hereinafter described, the form-block and platen move upwardly, until the plunger 20 resumes its original position, the form-blocks 17 and 18, however, continuing their upward travel beyond that point. Suitable stripping mechanism, not shown, forces the wrapped box from the form-blocks, leaving it on the platen 19 from which position it is ejected by a reciprocating member 21 operating in timed relation to the movements 75 of the rocker arm 3.

The oppositely disposed pairs of units 22, 22 and 23, 23 for effecting the several wrapping operations are adjustably mounted upon a table member 24 or the like at the top of the casing 1. As the box B with a wrapper W adhering thereto is moved downwardly by the form-block structure the side panels 25, 25 are engaged by rolls 26 carried by units 22 and which have been moved into the path 80 of the form-block structure by cam mechanism not shown, operating in timed relation to the descent of the plunger, to fold the panels into engagement with the side walls 95 of the box. Thereafter the turn-in fingers 100

27 during continued downward movement of the box engage and fold the corner lap sections 28 of the wrapper into adhesive engagement with the end walls 29 of the box. 5 As the box continues its downward movement the end panels 30 of the wrapper are engaged by rolls 31, 31, of units 23, which are moved into the path of the descending blocks by cam or other suitable mechanism, 10 not shown, to fold the end panels into engagement with the end wall 29 of the box and with the turned-in corner lap sections 28.

The mechanism thus far described and its mode of operation is substantially similar to 15 that of prior patents including Smith Patent 691,329, Nitsch et al. Patent 1,540,900, Federwitz et al. Patent 1,541,036 and Reifsnyder et al. Patent 1,152,356. Prior to my invention when some types of wrapper paper were 20 used, deep boxes wrapped, and particularly and practically in all cases where high speed operation was attempted, the wrapped box was often and usually disfigured by mutilation or tearing of the end panels adjacent the 25 lower corners of the box. It now appears that during descent of the box, the resistance offered by the air or atmosphere was sufficient to effect movement of the end panels 30 of the wrapper into the path of movement of 30 the corner lap sections 28, as shown in Fig. 5, so that when the turn-in fingers 27 forced the corner lap sections into engagement with the end wall 29 of the box, the end panel 30 of the wrapper was torn or badly crumpled, 35 as shown in Fig. 6.

To avoid this difficulty, and to facilitate and to permit high speed of operation of the wrapping machine substantially in excess of that previously attainable, there is exerted 40 upon the end panels 30 a force to hold them away from the end walls of the box, as shown in Figs. 2 and 3 before and during the corner lap turn-in operation preferably a blast of air is directed, as by nozzles 32 against them. 45 The nozzles 32 are supported by members 33 mounted upon and movable with units 23, 23.

The air blast produced by pump 34 mounted upon base 2 and driven by any suitable means, as an electric motor 35, is conducted 50 through pipe 36 having a Y connection at its upper end from which extend the flexible tubes 37, 37 to pipes 38, 38 in communication with nozzles 32. The force of the blast, depending upon the nature or weight of the 55 wrapper W, the speed of descent of the form-blocks, etc. may be regulated as desired by adjustment of the bleeder valve 39 in communication with pipe 36 and atmosphere.

50 If desired a cut-off valve may be interposed in the air line, its operating mechanism being actuated in timed relation to the movement of the form-block structure to permit the blast to be effective only before and during the 55 turning in of the corner lap sections. There-

after the blast may be cut off during the remainder of the box-wrapping cycle.

The boxes with a coated wrapper adhering thereto may be individually placed upon the form-block structures 17, 18 by an operator, 70 or the wrapping machine may comprise a unit of a full automatic system in which wrappers and boxes are delivered thereto by mechanism operating in timed relation therewith, for example, in co-pending applications 75 of Federwitz and Bailey Serial No. 698,841, filed March 13, 1924; Serial No. 40,769, filed July 1, 1925; Serial No. 147,405, filed November 10, 1926; and Serial No. 321,635, filed November 24, 1928.

The wrappers W may be of the single piece type of individual wrapper having corner-cut notches as shown in Stokes Patent 845,205, or of the composite type disclosed in Stokes Patent 1,625,577. Further the wrappers may be either untabbed, or provided with reinforcement strips or tabs, for example, as shown in Stokes Patents 1,599,500, 1,273,420, 845,205, or in co-pending Stokes applications Serial No. 303,688, filed September 4, 1928; 90 Serial No. 225,472, filed October 11, 1927; 79,936, filed January 8, 1926; and 88,231, filed February 15, 1926. The boxes B may be stayed boxes, one-piece blanks, or composite blanks of a plurality of components as in 95 Stokes et al. Patent 1,265,273.

What I claim is:

1. The method of wrapping a box which comprises moving a box and a wrapper along a path, at a point or region in said path folding a portion of the wrapper into engagement with a box wall, and applying a force to another wrapper portion to prevent movement thereof into the path of movement of the first portion during said folding operation. 100

2. The method of wrapping a box which comprises moving a box and a wrapper along a path, at a point or region in said path and during movement of the box and wrapper folding a portion of the wrapper into engagement with a box wall, and applying a force to another wrapper portion to prevent movement thereof into the path of movement of the first wrapper portion during said folding operation. 110

3. The method of wrapping a box which comprises moving a box and a wrapper along a path, at a point or region in said path folding a portion of the wrapper into engagement with a box wall, and applying a blast of air to another wrapper portion to prevent movement thereof into the path of movement of the first portion during said folding operation. 115

4. The method of wrapping a box which comprises moving a box and a wrapper along a path, at a point or region in said path and during movement of the box and wrapper folding a portion of the wrapper into engagement with a box wall, and applying a blast 120

of air to another wrapper portion to prevent movement thereof into the path of movement of the first wrapper portion during said folding operation.

5. The method of wrapping a box which comprises moving a box and a wrapper along a path, at a point or region in said path folding a portion of the wrapper into engagement with a box wall, applying a force to another wrapper portion to prevent movement thereof into the path of movement of the first portion during said folding operation, and thereafter folding the second wrapper portion into engagement with the first 15 wrapper portion.

6. The method of wrapping a box which comprises moving a box and wrapper along a path, at a point or region in said path and during movement of the box and wrapper 20 folding a portion of the wrapper into engagement with a box wall, applying a force to another wrapper portion to prevent movement thereof into the path of movement of the first wrapper portion during said folding 25 operation, and thereafter folding the second wrapper portion into engagement with the first wrapper portion.

7. The method of wrapping a box which comprises moving a box and wrapper along 30 a path, at a point or region in said path moving wrapper portions toward each other and into engagement with a box wall, and applying a force to a wrapper portion adjacent said first named portions to prevent its movement 35 into the path of movement of said portions during the folding operation.

8. The method of wrapping a box which comprises moving a box and wrapper along a path, at a point or region in said path and 40 during movement of the box and wrapper moving wrapper portions toward each other and into engagement with a box wall, and applying a force to a wrapper portion adjacent said first named portions to prevent its 45 movement into the path of movement of said portions during the folding operation.

9. The method of wrapping a box which comprises moving a box and wrapper along a path, at a point or region in said path moving 50 wrapper portions toward each other and into engagement with a box wall, and applying a blast of air to a wrapper portion adjacent said first named portions to prevent its movement into the path of movement of said 55 portions during the folding operation.

10. The method of wrapping a box which comprises moving a box and wrapper along a path, at a point or region in said path and during movement of the box and wrapper 60 moving wrapper portions toward each other and into engagement with a box wall, and applying a blast of air to a wrapper portion adjacent said first named portions to prevent its movement into the path of movement of said 65 portions during the folding operation.

11. The method of wrapping a box which comprises moving a box and a coated wrapper adhering thereto along a path, at a point or region in said path folding a portion of the wrapper into adhesive engagement with a box wall, and applying a force to another wrapper portion to prevent movement thereof into the path of movement of the first portion during said folding operation. 75

12. The method of wrapping a box which comprises moving a box and a coated wrapper adhering thereto along a path, at a point or region in said path and during movement of the box and wrapper folding a portion of the wrapper into engagement with a box wall, 80 and applying a force to another wrapper portion to prevent movement thereof into the path of movement of the first wrapper portion during said folding operation.

13. The method of wrapping a box which comprises moving a box and a coated wrapper adhering thereto along a path, at a point or region in said path folding a portion of the wrapper into adhesive engagement with a box wall, 85 applying a force to another wrapper portion to prevent movement thereof into the path of movement of the first portion during said folding operation, and thereafter folding the second wrapper portion into adhesive 90 engagement with the first wrapper portion. 95

14. The method of wrapping a box which comprises moving a box and a wrapper along a path, at a point in said path turning in corner lap sections of the wrapper into engagement with the end wall of the box, and directing a blast of air against an end panel of the wrapper to prevent its movement in the path of movement of the corner lap sections during said turn-in operation. 100

15. The method of wrapping a box which comprises moving a box and a coated wrapper adhering thereto along a path, at a point in said path turning in corner lap sections of the wrapper into adhesive engagement with the end wall of the box, and directing a blast of air against an end panel of the wrapper to prevent its movement in the path of movement of the corner lap sections during said turn-in operation. 105

16. The method of wrapping a box which comprises moving a box and a wrapper along a path, at a point in said path turning in corner lap sections of the wrapper into engagement with the end wall of the box, directing a blast of air against an end panel of the wrapper to prevent its movement in the path of movement of the corner-lap sections during said turn-in operation, and thereafter folding the end panel of the wrapper into engagement with the turned-in corner lap sections. 110

17. The method of wrapping a box which comprises moving a box and a coated wrapper adhering thereto along a path, at a point in said path turning in corner lap sections of 115

the wrapper into adhesive engagement with the end wall of the box, directing a blast of air against an end panel of the wrapper to prevent its movement into the path of movement of the corner-lap sections during said turn-in operation, and thereafter folding the end panel of the wrapper into adhesive engagement with the turned-in corner-lap sections.

18. A wrapping machine comprising form-block structure adapted to transport a box and a wrapper, means to fold a portion into engagement with the box, and means to apply a force preventing movement of another wrapper portion into the path of movement of said first portion during said folding operation.

19. A wrapping machine comprising form-block structure adapted to transport a box and a wrapper, means operating in timed relation to said form-block structure to fold a portion into engagement with the box during movement thereof, and means to apply a force preventing movement of another wrapper portion into the path of movement of said first portion during said folding operation.

20. A wrapping machine comprising form-block structure adapted to transport a box and a wrapper, means to fold a wrapper portion into engagement with the box, a nozzle positioned adjacent the path of movement of said form-block structure, and means to deliver air under pressure to said nozzle to prevent another wrapper portion from being engaged by said first named means during folding of the first wrapper portion.

21. A wrapping machine comprising form-block structure adapted to transport a box and a wrapper, means to fold oppositely disposed wrapper portions into engagement with the box, and nozzles positioned adjacent the path of travel of the form-block structure to direct a blast of air against other wrapper portions to be subsequently applied to the box.

22. A wrapping machine comprising form-block structure adapted to transport a box and a wrapper, means adjustably positioned adjacent the path of travel of said form-block structure to fold a wrapper portion into engagement with a wall of the box, and a nozzle carried thereby and adjustable therewith adapted to direct a blast of air against said wrapper portion.

THEODORE A. FEDERWITZ.
